METHOD OF SHAPING RAIL JOINT BARS

George Langford, Joliet, Ill.

Application December 5, 1935, Serial No. 53,035

3 Claims. (Cl. 29—169.1)

My invention is a method of shaping joint bars used for coupling rails together to form a railway track. More particularly it is a bending operation intended to deflect portions of a bar's length. This may be distinguished from cross-sectional shaping, in that my method merely deflects portions of the bar's length without appreciable flow of metal such as would materially alter the cross-section of the bar at any point throughout its length. My method reshapes the bar's length but is not intended to alter its cross-section, and is particularly directed to a bar of angle type whose bottom member extends more laterally outward than the top member. From the following description, those skilled in the art will understand the method I claim and recognize its advantages.

In the drawings:

Fig. 1 is an end view of an angle beam illustrating the ordinary difficulty encountered in deflecting a portion of its length;

Fig. 2 is an end view of an angle bar deflected in a worn rail joint;

Fig. 3 is a side view of the rail joint of Fig. 2 with the bolts removed, and the rails made continuous;

Fig. 4 is an end view of a pair of dies used to deflect portions of a bar in accordance with the method of my invention;

Figs. 5 and 6 are fragmentary plan views of the top portion of the bottom die of Fig. 4;

Fig. 7 is a plan view of the bottom die, illustrating a variation of the method of my invention;

Fig. 8 is a side view of a bar produced in the die of Fig. 7;

Fig. 9 is a plan view of the top surface of a bar whose intermediate portions are deflected outward and downward.

Figs. 10 and 11 are plan views of variously deflected top surfaces of bars.

In the deflection of an angle form of bar, a certain difficulty is encountered, the result of a simple mechanical principle.

Fig. 1 is an end view of beam 1 of angle form shown in full lines. This angle form of beam is to be compared with an angle bar in a rail joint under direct load, loaded in the middle and supported at its ends.

If vertical load VL or VL^2 , or both, are applied to the middle of the angle beam, it might be thought that this would deflect the middle of the beam vertically downward. But this alone does not happen. The middle of the bar deflects downwardly and inwardly as per the arrow D. The same is true under horizontal loads HL or HL^2 or both. The reason for this is that the stiffness of the angle form is least in the direction of the arrow D, and so the angle bar bends in that direction. The middle of the bar instead

of deflecting horizontally, bends downwardly as it bends inwardly. In both forms of loading, the bar bends diagonally so that its ends are at $a-b-e-d-c$ and its middle at $a'-b'-e'-d'-c'$. In other words, under direct load, the middle of the bar bends downward as it is bent inward or bends inward as it is bent downward.

An angle bar in a joint behaves similarly, as shown in Fig. 2, the lettering being the same as in Fig. 1. This shows what happens when the joint becomes worn.

It is known that a joint usually wears more at its center than at its ends. To take up this wear and thus maintain a central fit, the bar is bent in at center by pressure caused by tightening up the center bolts. This pressure is represented by HL , the equivalent of the horizontal load in Fig. 1. Instead of moving in horizontally at center, the top fishing surface $a-b$ of the bar moves inwardly and downwardly to $a'-b'$. The bottom fishing surface $c-d$ does the same thing. It moves in and down to $c'-d'$, and because of the pressure on $c'-d'$ at center and the gap between the rail ends at center, the ends of the rails are forced downward resulting in a "low" joint. This inherent tendency to diagonal deflection is disagreeable but unavoidable. The angle form can bend in no other way. To properly take up wear, the fishing surfaces $a-b$ and $c-d$ should move in at least horizontally but not downwardly. The fact is that they should move a little upwardly at center as they are bent in, for the reason that central wear is usually greater at the top than at the bottom, therefore surface $a-b$ as it is moved inwardly, should move upwardly, never downwardly to $a'-b'$ as shown in Fig. 2.

To properly deflect portions of the length of an angle bar for particular purposes, its above described tendency to diagonal deflection must be overcome. The top surface $a-b$ when bent in, must bend not downwardly, but at least horizontally and preferably upward.

Fig. 3 is an outside view of the joint of Fig. 2 with the bolts removed. If the gap between the rails were removed and the rails made continuous, the rails would more strongly resist the tendency of the bar when deflected inwardly at center to force them downward. Going further, if the bar were hot and plastic, and the rail cold and unyielding, instead of the center of the bar forcing the rail ends down, the rails would force the center of the bar up. Proceeding on this basis with Fig. 3, the rail herein made continuous by closing the central gap and retaining the worn recess $b-b'-b'-b$, might be used as a cold die to properly deflect selected portions of a heated bar, and instead of center bolt tension, other pressure means could be employed.

In Fig. 4, 3^a is an end view of a forming die equivalent to the rail 3 of Fig. 3 made rigid and non-resistant. 4 is an end view of an upper die or means for applying deflection pressure. This 5 is broadly equivalent to center bolt tensions 4² in Fig. 3. The bottom 5 of the recess of the bottom die is equivalent to the rail web profile 5^a of Fig. 2. The die wall has a recessed surface b'-a', equivalent to the worn recess 10 b-b'-b'-b of the rail in Fig. 3. By comparing this surface b'-a' with that of Fig. 2, it may be seen that it is above or outside of surface a-b instead of being below or inside as in Fig. 2.

15 In Fig. 4, surface 5 of die 3^a may be straight, not convexed, throughout the die from end to end. In the die is a bar 6 with a portion 7 deflected downwardly. The top die 4 is in its closed position with pressure P on portion 1 of 20 the bar but not on portion 6. The reactions R of pressure P by the top die are carried on the fishing surfaces a-b and c-d by the bottom die. With no pressure on portion 6, the bar is held up on the die surfaces a-b and c-d while 25 portion 7 is deflected under pressure P with the resulting positioning of surfaces a-b and a'-b' as shown. This is not a simple bending method, for it does not result in the objectionable diagonal deflection shown in Figs. 1 and 2. Nor is it a 30 reforming operation whereby the bar is shaped to the dies. In its application, it utilizes the principle of load and reactions on a beam supported by reactions on each side of the load.

Fig. 5 is a simplified fragmentary head portion of die 3^a of Fig. 4 viewed from above. The 35 position of a bar head in the die is indicated by dotted lines. b, equivalent to a-b in Fig. 4, represents the recessed surface of the die from which the bar is to be deflected to the plane b'. 40 The bending pressure is applied at P, none at R where the reactions to pressure P are carried on the two surfaces b and the two corresponding surfaces in the opposite bottom wall not shown. If as in Fig. 6, pressure were applied 45 on two places at P and their reactions carried between them at R, there would be two deflections to b'. The two variations of deflections in Figs. 5 and 6 are then applied to a full length bar in Fig. 7. Here are three applied pressures 50 P; at the center C, and at the two end portions E of the bar. There are two reactions R; one between the central portion and each end portion making undeflected portions I. The resultant bar would be as in Fig. 8 which is an 55 outside view of the bar of Fig. 7. The central portion C and end portion lengths E are deflected under pressure so as to provide corresponding rail fishing surfaces, and the undeflected lengths I carrying reactions R remain 60 as rail clearances. A top view of the top surface of another form of bar is shown in Fig. 9. The fishing surfaces are deflected in to the rail at C and E, and the surfaces of I are left remaining laterally outward, clear of the rail. 65 In this case, portions I are left deflected outwardly and also downwardly so that there may be no intermediate rail clearance at the bottom. The parts I may be placed closer to the rail head by applying pressures instead of reactions 70 at I. The inner under surface of the bar head having no die wall contact would then be in

part depressed and there would be little or no projection of the bar laterally and beyond the side of the rail head. In such a case, the reactions to pressure would be carried on the die surfaces corresponding to the bar's clearance 5 surfaces at I.

Fig. 10 is the top fishing surface of a bar viewed from above. This is an incurved form produced as in Fig. 5. Fig. 11 is a similar view with rail clearance at I, made as previously described. 10 These and other forms of bars resulting from variations of deflection may be made by my method of combining deflection under pressure with lack of deflection under the reactions to said pressure.

15 Obviously there may be advantage in heating only the portion of the bar which is to be deflected, for then the portions on each side of the deflected portion would better resist any tendency of the pressure at the deflected portion to 20 extend to the portions where deflection is not desired and deflect them also. Bars so heated when quenched in oil would be harder at the deflected portion, and softer at the undeflected portions, which in some cases would be a desirable result to attain, a particular instance being a bar deflected inwardly at its central portion.

What I claim is:—

1. The method of deflecting inwardly the center portion of an angle form of rail joint bar so as to provide top and bottom fishing contact with worn rails at the center portion and end portions of the bar, consisting in heating said center portion and subjecting said center portion only to bending pressure so as to force it inwardly to the planes of top and bottom rail fishing contact, said center portion being restrained from downward deflection, and said end portions being restrained from inward deflection beyond the planes of top and bottom rail fishing contact. 30

2. The method of deflecting inwardly the center portion and end portions of an angle form of rail joint bar so as to provide for top and bottom rail contacts at said center portion and end portions, and intermediate rail clearances between said center portion and end portions, consisting in heating the bar and subjecting said center portion and end portions to pressure so as to force them inwardly to the planes of top and bottom rail contact, said center portion being restrained from downward deflection, and said intermediate portions being restrained from inward deflection at the top at least so as to provide top intermediate rail clearances. 45

3. The method of deflecting inwardly longitudinal portions of an angle form of rail joint bar so as to provide top and bottom rail contact at said inwardly deflected portions and less effective fishing height of the bar at adjacent portions, consisting in heating said portions and subjecting said portions only to pressures so as to force them inwardly to the planes of top and bottom rail contact, said inwardly deflected portions being restrained from downward deflection, and said adjacent portions being restrained from inward deflection beyond planes of lesser effective fishing height than at said inwardly deflected portions. 60

GEORGE LANGFORD. 70
